PIPE FLASHING

Robert H. Dammer, Manchester, Conn., assignor to Uni-royal, Inc., New York, N.Y., a corporation of New Jersey

Filed Mar. 26, 1968, Ser. No. 11,146

Term of patent 14 years

Int. Cl. D23—01

U.S. Cl. D23—42

FIG. 1 is a perspective view of a pipe flashing showing my new design;

FIG. 2 is a cross sectional view taken on line 2—2 of FIG. 1; and

FIG. 3 is an enlarged fragmentary cross sectional view taken on line 3—3 of FIG. 2.

I claim:

The ornamental design for a pipe flashing, as shown.
